Attorney,

UNITED STATES PATENT OFFICE.

MILTON E. PUGH, OF DAYTON, OHIO, ASSIGNOR OF ONE-THIRD TO LEO C. POLLOCK AND
ONE-THIRD TO FRANK HARTMAN, OF DAYTON, OHIO.

WINDOW-CLEANING DEVICE.

Specification of Letters Patent.

Patented Oct. 6, 1914.

1,113,165.

Application filed August 16, 1913. Serial No. 785,113.

To all whom it may concern:

Be it known that I, MILTON E. PUGH, a citizen of the United States, residing at Dayton, in the county of Montgomery and State of Ohio, have invented certain new and useful Improvements in Window-Cleaning Devices, of which the following is a specification, reference being had therein to the accompanying drawing.

10 This invention relates to window cleaning devices and is designed particularly for use with windows in the vestibules of street cars, the windows of engine cabs and in similar positions.

15 The object of the invention is to provide means whereby rain, snow or other accumulations may be quickly and easily removed from the exterior of the window and the window itself quickly dried.

20 To this end it is a further object of the invention to provide a plurality of sashes so arranged that either of them may be moved into position to close the window opening and the other moved into an inoperative

25 position, preferably into a pocket in the frame of the car; also to provide means whereby the movement of one of the sashes into the pocket in the frame will cause the accumulations of rain, snow or the like to be removed from the exterior thereof; and 30 also to provide means whereby the glass may be dried while the sash is in its inoperative position.

35 In the accompanying drawings, Figure 1 is a perspective view of the exterior of a window equipped with my invention; Fig. 2 is a vertical section, taken through such a window and showing the connecting devices between the two sashes; and Fig. 3 is 40 a sectional view taken through one of the wipers.

45 In these drawings I have illustrated one embodiment of the invention and have shown the same as applied to the front window of a street car vestibule, the wall of which is indicated at 1 and the frame of the window at 2. Mounted in the window frame are two sashes, 3 and 4, either of which when in its uppermost position will close 50 the window opening. The wall of the car beneath the window opening is provided with a pocket 5, into which either sash may be moved. The two sashes are preferably connected one to the other so that as one 55 is moved upward the other will be moved

downward and the act of moving one will impart movement to the other. In the present instance this connection is formed by means of sprocket chains 6 and 7. Each sprocket chain 6, of which there are preferably two, extends about a sprocket wheel 8 journaled in a suitable housing 9 mounted in the upper part of the window frame, and is connected at its ends to the upper edges of the two sashes. Each of the other 60 sprocket chains 7, of which there are also two, extends about a sprocket wheel 10 journaled in a similar housing 11 mounted in the frame of the car near the bottom of the pocket 5 and is connected at its ends to the 65 lower edges of the two sashes. Suitable wipers are arranged to remove the moisture from the glass of each sash as it is moved downward. In the present instance, these wipers are in the form of squeegees 12 and 70 13, the squeegee 12 being mounted upon the window sill and arranged to engage the glass of the outer sash 4 when the latter is moved downward. The squeegee 13 is mounted upon the top of the sash 4 and will 75 engage the glass of the sash 3 as the two sashes move relatively one to the other, thus wiping the moisture from the exterior of the glass of the sash 3. These squeegees preferably engage the glass with a yielding pressure and to this end each is movably mounted upon its supporting structure and is held in engagement with the glass by means of a 80 spring. As here shown the window sill has formed therein, near each end thereof, a recess in which is mounted a housing 14 having its upper end open. The squeegee 12 is provided with a depending lug 15 which extends into the housing 14 and has an aperture through which a pin 16 loosely extends. 85 This pin 16 extends through the outer end of the housing and is screw-threaded into the inner end of the housing. The ends of the pin extend through the adjacent portions of the window sill, or sash as the case 90 may be, and serve to hold the housing in position. A spring 17 is coiled about the pin 16 between the lug 15 and the outer wall of the housing and tends to move the squeegee 95 toward the window. By removing the pin 16 the squeegee can be removed and renewed when the flexible or wiping portion thereof becomes worn.

100 It will be apparent that with the construction above described each sash may be 110

cleaned by the mere act of moving the same downward into an inoperative position and that this act will simultaneously move the other sash into operative position. By providing the squeegees with sufficient flexibility they may be used with sash of ordinary construction but to enable them to more readily pass the ends of the sash I prefer to mount the glass substantially flush with the face of the sash. In the present instance this is accomplished by securing the glass in place by the use of thin metal strips 20.

It is desirable that means should be provided to dry the glass of the sash which is in the pocket 5 and to this end I mount within the pocket 5 a suitable heater which, in the present instance, is shown as comprising a radiator 18 having a series of coils of pipe which may be connected with the heating system of the car or other suitable source of heat supply. This heater is so arranged relatively to the sash which is in the pocket that the heat will be distributed over the same evenly and the glass of the sash will be very quickly dried after it has been moved into the pocket 5, thus enabling the sashes to be frequently shifted from one position to the other and a clean dry window provided at frequent intervals. It will also be noted that the wipers or mops extend beyond the edges of the glass and have resilient or felted portions engaging the sash on the opposite sides of the glass, thereby constituting weather strips and effectually preventing the entrance of cold air into the car through the window frame.

While I have shown and described one embodiment of my invention it will be understood that this has been chosen for the purpose of illustration only and that I do not desire to be limited to the details of construction shown and described, except as limited by the appended claims for obvious modifications will occur to a person skilled in the art.

Having thus fully described my invention, what I claim as new and desire to secure by Letters Patent, is:

1. In a window cleaner, two sashes operatively connected one to the other, whereby when either sash is moved into an inoperative position the other sash will be moved into an operative position, and means for automatically cleaning the glass of that sash which is being moved into an inoperative position.

2. The combination, with a window frame having a pocket, two sashes mounted in said frame, either of which is adapted to close the window opening and either of which may be moved into said pocket, a connection between said sashes to cause one of them to be moved into position to close said window opening when the other is moved into said pocket, and means arranged to automati-

cally clean the glass of that sash which is being moved into said pocket.

3. The combination, with a window frame having a pocket, two sashes mounted in said frame, either of which is adapted to close the window opening and either of which may be moved into said pocket, a connection between said sashes to cause one of them to be moved into position to close said window opening when the other is moved into said pocket, means arranged to automatically clean the glass of that sash which is being moved into said pocket, and means arranged within said pocket to dry the glass of that sash which has been moved into said pocket. 80

4. The combination, with a window frame, of two sashes mounted in said frame and connected one with the other to cause them to move simultaneously in opposite directions, a wiper carried by said frame and arranged to wipe the glass of one sash when movement is imparted to said sash, and a second wiper mounted upon said first-mentioned sash and adapted to wipe the glass of the second sash when movement is imparted to said second sash. 85

5. The combination, with a window frame, of two sashes mounted in said frame and connected one with the other to cause them to move simultaneously in opposite directions, a wiper carried by said frame and arranged to wipe the glass of one sash when movement is imparted to said sash, and a second wiper mounted upon said first-mentioned sash and adapted to wipe the glass of the second sash when movement is imparted to said second sash, and a drier arranged adjacent to the position occupied by said sashes when in their inoperative positions. 95

6. The combination, with a window frame comprising a window opening and a pocket arranged beneath said opening, of two sashes mounted in said frame, either of which may be moved into a position to close said window opening or into said pocket, a wiper carried by said frame to wipe the glass of one of said sashes as it is moved downward, and a second wiper carried by the first-mentioned sash to wipe the glass of the other sash as it is moved downward. 110

7. The combination, with a window frame comprising a window opening, and a pocket arranged beneath said opening, of two sashes mounted in said frame, either of which may be moved into a position to close said window opening or into said pocket, a wiper carried by said frame to wipe the glass of one of said sashes as it is moved downward, a second wiper carried by the first-mentioned sash to wipe the glass of the other sash as it is moved downward, and a drier arranged within said pocket. 120

8. The combination, with a window frame comprising a window opening, and a pocket 130

arranged adjacent said opening, of two sashes mounted in said frame, either of which may be moved into a position to close said window opening or into said pocket, a 5 wiper removably mounted on said frame to wipe the glass of one of said sashes as it is moved toward its inoperative position, and a second wiper removably mounted on the first-mentioned sash to wipe the glass of 10 the other sash as it is moved toward its inoperative position.

9. In a window, a pair of vertically mov-

able sashes positively connected together for opposed vertical movements, and means for automatically cleaning the glass of the 15 sashes when said sashes are alternately moved downwardly.

In testimony whereof, I affix my signature in presence of two witnesses.

MILTON E. PUGH.
